DESIGN FOR A COMBINATION BUFFING AND SCRAPING TOOL FOR TIRES OR THE LIKE

Samuel Evans Parker, Dunkirk, Ind.

Application February 23, 1940, Serial No. 90,467

Term of patent 7 years

To all whom it may concern:

Be it known that I, Samuel Evans Parker, a citizen of the United States, residing at Dunkirk, in the county of Jay and State of Indiana, have invented a new, original, and ornamental Design for a Combination Buffing and Scraping Tool for Tires or the like, of which the following is a specification, reference being had to the accompanying drawing, forming part thereof.

Figure 1 is a side elevational view of a combination buffing and scraping tool for tires or the like showing my new design.

Figure 2 is a top plan view of the tool illustrated in Figure 1, and

Figure 3 is a bottom plan view of the tool illustrated in Figure 1.

I claim:

The ornamental design for a combination buffing and scraping tool for tires or the like, as shown.

SAMUEL EVANS PARKER.
